PUMP

Francis W. Davis, Belmont, Mass.

Application July 28, 1936, Serial No. 93,034

2 Claims. (Cl. 103—128)

This invention relates to pumps, and more particularly to fluid pumps of the rotary gear type.

The principal object of the invention is to provide, in a rotary gear pump or in a pump of similar design or operation, novel details of construction which render the pump extremely economical of manufacture as well as satisfactory of operation.

Other objects of the invention are to provide novel means for equalizing end thrust on the rotary gears or pumping elements, novel means for insuring force feed lubrication of the bearings of rotating elements of the pump, and novel means for sealing a pump drive shaft to a pump casing.

Still further objects of the invention will be readily apparent to those skilled in the art to which the invention appertains upon reference to the following detailed description of an embodiment, chosen by way of example and disclosed in the appended drawings. In these drawings—

Figure 1 is a vertical section, as if on the line 1—1 of Figure 2.

Figure 2 is a horizontal section, as if on the line 2—2 of Figure 1.

Figure 3 is a partial vertical section, as if on the line 3—3 of Figure 1.

Figure 4 is a side view, as if from the right of Figure 1, with parts cut away for purposes of clarity.

Figures 5 and 6 are details in section, as if on the lines 5—5 and 6—6 of Figures 3 and 4, respectively.

The pump shown in the drawings includes a pump casing 10, having an open top provided with a top ledge 10a and a tank 11, mounted thereon and secured thereto by screws 12.

The pump casing includes a driving end section 14, a center section 15, and a delivery end section 16, maintained in alignment by dowels 17 disposed in aligned bores of the sections, the bores being closed by dowel plugs 18, and relatively secured by elongated cap screws 19, of which there are eight shown. The sections may be joined 45 to form a complete pump casing, now to be described in detail.

In the lower and forward corner of the right side wall 20 of section 16 (Figure 4) is a hole 21 into which may be connected an inlet pipe, not shown, the hole establishing communication between the inlet pipe and a cavity 22 which opens into cavities 23 and 24 of center section 15 (Figure 3). Cavity 24 of section 15 in turn opens into the inlet or low pressure side of the substantially oval pump or gear chamber 26 through

a trumpet-shaped vertical inlet opening 27, the open sides of the chamber 26 and inlet 27 being closed by vertical webs 28 (Figure 1) formed as part of the end sections 14 and 16, these webs corresponding roughly in shape to the shape of 5 the peripheral wall 29 of the gear chamber 26.

In one of those portions of the upper part of delivery end section 16 which connects web 28 to wall 20 is a horizontal bore 31 (Figure 1), which passes through web 28 and wall 20 and opens 10 into the upper part of pump chamber 26 to form an outlet thereof, and which has a threaded part 32 adjacent side wall 20, to receive an outlet pipe, not shown.

Disposed within gear chamber 26 dividing the latter into a low pressure side (near inlet 27) and a high pressure side (near outlet bore 31), are the pumping gears (Figure 3), of which there are a driving gear 34 and a driven gear 35, both having meshing helical teeth of the segmental form 20 shown, it being understood that other suitable gear teeth may be provided, if desired. These gears pump fluid from the inlet 27 to the outlet bore 31, in a manner well known to those acquainted with fluid pumps of the geared type. 25

The driving gear 34 is supported on and keyed to a driving gear shaft 36 and fits relatively closely, though without binding, between the side walls of chamber 26, namely webs 28. The driving shaft 36 (Figure 2) is journaled in bearings 37, 37a 30 and 38, press fitted into bores 39 and 40 of sections 14 and 16, bearings 37 and 37a being in the same bore and being relatively separated, as shown, by an annular space 41.

One end of shaft 36 projects through a stuffing box on the left side wall of section 14 to be connected to a driving device, such as a motor or the like, the stuffing box comprising a boss 42 projecting from the wall, suitable packing 43 therein, and a cover 44 threaded thereon. 35

The other end of the driving shaft is counter-bored, as at 46, to receive a thrust equalizing plug 47 provided with annular grooves 48 and a head 49, adjacent to the end of the bearing 38, the latter having a notch 50 in its end. The end of 40 the bearing 38 forms a shoulder around and beyond the end of the shaft 36. The head 49 of the plug 47 seats on said shoulder, restraining the plug from exerting any axial thrust on the shaft by contact with either the annular end face of 45 the shaft or the inner end of the hollow. An end plug 51 threaded into a threaded enlargement 52 of bore 40 closes the latter. 50

The driven gear 35 is supported and journaled on the driven gear shaft 54 and also fits relatively

closely, though without binding, between the side walls of chamber 26, namely, webs 28. The shaft 54 (Figure 2) is journaled in bearings 55 and 56 press fitted into bores 57 and 58 of sections 14 and 16. The driven shaft has an axial bore 59 therethrough and a counterbore 61 at its left end receiving a thrust equalizing plug 62 provided with annular grooves 63 and a head 64 adjacent to the end of the bearing 55, the latter having a notch 55a in its end. An end plug 65 threaded into a threaded enlargement 66 of bore 57 closes the latter. The enlargement 67 of bore 58 at the right end of the shaft 54 receives an end plug 68, which closes the bore 58.

15 Since the gears 34 and 35 are helical, it is evident that the interfacial pressure of their contacting teeth will have components parallel to gear axes, these components resulting in an end thrust in one direction on one gear shaft and 20 an equal and opposite end thrust on the other shaft. According to the present invention, means are provided to equalize or counteract these end thrusts. As shown in Figures 4 and 6, a duct 70 is provided connecting the high pressure side of 25 the pump chamber, namely, the outlet bore 31, to the space in bore 40 and its enlargement 52 between the head 49 of the thrust equalizing plug and the end of the shaft 36.

Fluid under outlet pressure (high) acts on the 30 annular end face of the shaft 36 and exerts an endwise thrust on the driving shaft 36 towards the left. The plug 51 acts as an abutment for plug end 49 in one direction and the bushing 38 acts as an abutment for plug end 49 in the other 35 direction.

A portion of the fluid will pass into the counterbore 46 and the partial bore 71 of the shaft (Figures 2 and 6), and will pass to the left end of the driving shaft. This portion of the fluid will work its way through the transverse shaft relief ducts 73 in the left end of the shaft and into the annular space 41 between bushings 37, 37a, escaping from this space, through ducts 75 (Figure 1) to the low pressure side cavity 76 in section 14 connected to the low pressure side cavity 24 of section 15.

Connecting the high pressure side of the gear chamber, namely that part above the gears therein, to the space in bore 57 and its enlargement 66 between the head 64 of thrust equalizing plug 62 and the end plug 65 are a bore 77 (Figures 3 and 5) and a thrust equalizing duct 78.

Fluid under outlet pressure (high) works into 55 the space between plug end 64 and the end of the shaft 54, thus exerting an endwise thrust on the driven shaft towards the right. The plug 65 and the bushing 55 act as abutments for the plug end 64, thus holding it in place.

60 A portion of the fluid will pass into the counterbore 61 and the bore 59 of the shaft and will pass to the right-hand end of the shaft. This portion will return to the low pressure side of the pump through a vertical duct 79 (Figures 2 and 4), connecting bore 58 at the right-hand end of the shaft to the low pressure cavity 22.

It is evident that by reason of the axial bores in the shafts 36 and 54, each shaft has a plurality of axially spaced face areas facing in the direction of the impressed axial thrust so as to receive the thrust of liquid pressure opposed to the impressed axial thrust, the effective components of such areas on each shaft equalling the cross-sectional area of the shaft. High-pressure fluid 75 is directed against some of these areas by con-

nection with the discharge side of the pump, low-pressure fluid being directed against the others by connection with the suction side of the pump. By suitably proportioning the high-pressure and low-pressure areas, the proper equalizing thrusts 5 on the shafts are obtained.

The shaft relief ducts 73, the space 41, and the return ducts 75 create a fluid seal, on the left-hand end of the driving shaft, to prevent air from outside the pump casing passing into the 10 pump housing through the space around the end of shaft 36. A certain amount of high pressure fluid will escape from the pump housing 26 between the shaft 36 and the bushing 37. However, this pressure fluid will flow to the low 15 pressure chamber through the space 41 and ducts 75.

This seal will not, however, prevent the leakage 20 of fluid from the low pressure side of the pump to the outside thereof, such escape being prevented by the packing 43. However, the packing is not subjected to the higher fluid pressure but only to the lower fluid pressure, the seal at 13, 41 and 75 isolating the gland from the high pressure side of the pump.

The circulation of fluid being pumped (often 25 oil for lubrication purposes) through and around the bearings at both ends of the shafts insures a force feed lubrication of these parts.

Suitable oil sealing ducts, such as the vertical 30 ducts 80 (Figures 2 and 3) and the horizontal ducts 81 (Figures 1 and 3), are provided to form oil seals between the walls of the center section 15 and the adjacent walls of the end sections 14 and 16.

These ducts are always in communication with the low pressure side of the pump casing and thus 35 form an oil seal entirely surrounding the pump. In this manner air is prevented from leaking into the pump chamber 26 under any and all conditions.

Air relief ducts 84 (Figures 2 and 4) are provided for relieving trapped air within the end 40 casing 16. The trapped air can readily escape to the upper portion of the casing 16 and from there into the tank 11.

The tank 11, previously mentioned as being disposed upon the pump casing 10, has a normally open bottom providing direct and unrestricted communication between the low pressure interior of the pump casing and the interior 50 of the tank, and has a closed top 90 provided with a filter type filler device, referenced generally at 91, the same not being described in detail since it forms no part of the present invention.

The tank is also provided with a relief valve 55 to relieve excessive pressures built up within the pump, the valve providing communication between the delivery or outlet side of the pump and the interior of the tank when the pump pressure becomes excessive. The relief valve (Figures 1 and 4) includes a valve seat ring 92 press fitted into a vertical bore 93 of the top 10a of pump section 16 to open communication 60 between the tank and the outlet bore 31, as indicated. Adapted to seat upon and guided within the valve seat ring is a valve proper 94 normally held against the upper beveled surface 96 of the seat by means of a spring pressed washer 97 engaging the top surface of the valve proper and 65 adapted to be moved downwardly by the valve spring 98, enclosed within the bracket 99 secured to the top ledge 10a of the pump section 16 by means of bolts 101. A suitable adjusting screw, 70 referenced generally at 102, is provided to deter- 75

mine the adjustment and capacity of the relief valve.

It will be observed that a pressure at the delivery or outlet end of the pump, in excess of that for which the valve spring is adjusted by the screw 102, will cause the valve proper 94 to move away from the seat vertically and permit escape of pumped fluid back to the low pressure interior of the tank 11.

10 In order to permit a gravity flow of fluid from the low pressure side of the pump casing to the outlet bore 31, when the pump is not working, the bore 77 (Figures 1 and 5) is provided with a port 108, connecting such bore to the interior 15 of the pump casing outside of the pump chamber, that is to say, to the low pressure side of the pump. This port may be closed by a ball check 109 adapted to be forced against the port 108 by the fluid pressure within the pump chamber when 20 the pump is working. However, when the pump is not working, and no pressure exists in the pump chamber, the ball 109 will drop or roll to the right as far as permitted by the retaining pin 111, sufficient to open the port 108 and permit 25 the flow of fluid by gravity from the tank 11 or from the interior of the pump casing into the pump chamber above the gears, and thence to the outlet 31.

From the foregoing, it will be observed that 30 there has been provided a fluid pump provided with suitable and satisfactory means for equalizing end thrust on the rotating pumping elements, means for insuring a force feed or pressure lubrication of the bearings of the rotating elements 35 of the pump, means creating a high pressure fluid seal between the drive shaft and the casing, thus preventing leakage around the pump shaft, and novel details of construction which make the

pump of the invention practical, economical of manufacture, and satisfactory of operation.

Now having described a preferred embodiment of the invention chosen by way of example, reference will be had to the following claims which 5 determine the scope of the invention.

I claim:

1. In a fluid pressure pump, a casing having a chamber therein, a pair of rotating pumping elements in said chamber each normally subject to 10 an axial reaction thrust from the other by mutual driving contact during operation and each having a shaft portion projecting into a wall of said casing in the direction of the axial thrust impressed thereon, and means for equalizing said 15 thrusts by fluid pressure applied to said shaft portions only, said means comprising means for introducing fluid from the discharge side of the pump between the end of each said shaft portion and an adjacent portion of said housing and 20 means for restricting the area of the shaft portion acted on by the pressure fluid to a predetermined fraction of its cross-sectional area.

2. In a fluid pressure pump, a casing having a chamber therein, a pair of helical pump gears 25 within said chamber, one of said gears being driven solely by its engagement with the other, whereby axial reaction thrusts are impressed on said gears in opposite directions during operation of the pump, a hollow shaft extending from 30 each said gear into the wall of said casing in the direction of axial thrust of its respective gear and open at its end, a plug fitted into the open end of each said hollow shaft, means for directing fluid pressure against the end area of each 35 shaft surrounding the opening therein, and means connecting the interior of the shaft with the low-pressure site of said pump.

FRANCIS W. DAVIS.
